CLAIM

The ornamental design for bone conduction earphones and case as shown and described.

DESCRIPTION

FIG. 1 is a front perspective view of bone conduction earphones and case, showing the new design, the case is shown separately for ease of illustration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the earphones of the bone conduction earphones and case, shown separately for ease of illustration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a front perspective view of bone conduction earphones and case thereof, in an open position.

The broken lines depict portions of the bone conduction earphones and case that form no part of the claimed design.

1 Claim, 15 Drawing Sheets
